CLAIM

The ornamental design for a pest-free feeder, as shown and described.

DESCRIPTION

FIG. 1 is a top perspective view of a pest-free feeder;
FIG. 2 is a top elevational view side view thereof;
FIG. 3 is a bottom elevational view side view thereof;
FIG. 4 is a front side view thereof;
FIG. 5 is a left side and right side vie thereof;
FIG. 6 is an exploded top perspective view thereof; and,
FIG. 7 is an enlarged view of a leg of the pest free feeder.
